[57] CLAIM

The ornamental design for an automobile light, as shown and described.

DESCRIPTION

FIG. 1 is a perspective view of an automobile light showing my new design, with the wires broken away to indicate indeterminate length;

FIG. 2 is a rear elevational view thereof, with the wires omitted for clarity of illustration only;

FIG. 3 is a top plan view thereof, with the bottom being a mirror image; and,

FIG. 4 is a right side view thereof.

The left side view is a mirror image of FIG. 4, and the bottom is a mirror image of the top.
